UNITED STATES PATENT OFFICE.

GEORGE R. COTTRELL, OF NEW YORK, N. Y.

GAS AND AIR MIXER.

SPECIFICATION forming part of Letters Patent No. 651,779, dated June 12, 1900.

Application filed August 25, 1899. Serial No. 728,431. (No model.)

To all whom it may concern:

Be it known that I, GEORGE R. COTTRELL, a citizen of the United States, residing at New York, (Tottenville,) in the county of Richmond and State of New York, have invented 5 certain new and useful Improvements in Apparatus for Mixing Gas and Air; and I do hereby declare the following to be a full, clear, and exact description of the invention, such 10 as will enable others skilled in the art to which it appertains to make and use the same.

This invention relates to apparatus for mixing gas and air or gaseous fluids of different gravities in the desired proportions under the 15 same pressure or velocity, and thereby obtaining a perfectly-homogeneous mixture of the gas and air or other fluid at a moderate pressure for supplying the burners of heating and cooking stoves and for other purposes.

20 In burning gas for heating and cooking purposes it is now a common practice to supply the current of gas to the burner-orifice at a comparatively-high velocity by means of an induction-burner of the Bunsen type, thereby 25 drawing in or inducing the flow of a current of air at a low velocity for mingling with the gas to cause combustion thereof. The results attained in practice are unsatisfactory and wasteful of gas for the reason that the 30 currents of gas and air moving at different velocities and the fluids being of different gravities do not diffuse and perfectly commingle, but, on the contrary, are held apart by a great law in nature, resulting in imperfect 35 and only partial combustion of the carbon particles and a corresponding waste of gas. Gases of different gravities, such as gas and air, must be united in positive measured proportions and also at the same velocity, so that 40 when they are brought together the mixture will be perfect and homogeneous and in uniform proportions.

The object of my invention is to provide 45 for overcoming the defects and objections in the gas and air mixing devices now in common use and to provide for mixing together currents of gas and air under a uniform pressure and at the same velocity and in positively-measured proportions, so as to obtain a perfectly-homogeneous mixture in uniform proportions, and thereby secure perfect combus-

tion and greater economy in the use of gas for heating, cooking, and other purposes.

In my improved gas and air mixing apparatus the air-meter drum and the gas-meter 55 drum are mounted upon the same shaft, and the pressure of gas is utilized for revolving the gas and air drums.

One of the special objects of my invention, therefore, is to reduce to the minimum the resistance to the revolution of the air and gas drums. This is accomplished by providing comparatively-narrow or small inlet-openings 60 to the screw measuring-compartments of the air and gas drums and comparatively wide or 65 large outlet-openings for the same.

Another object of my invention is to provide increased and more efficient driving surfaces or shoulders in the spiral vanes of the gas-meter drum, so that such drum shall be 70 more readily and effectively propelled by the pressure of the gas which is to be metered and mixed with the air.

The matter constituting my invention and improvements herein will be defined in the 75 claims.

I will now particularly describe my improved apparatus by reference to the accompanying drawings, in which—

Figure 1 represents a horizontal section of 80 the casing and meter-drums, excepting that the vanes in the drums are shown in plan view. Fig. 2 represents a vertical longitudinal section of the casing, with the meter-drums in elevation and illustrating diagrammatically by dotted lines the screw measuring-compartments of gradually-increasing diameter from the inlet ends to the discharge ends thereof. Fig. 3 represents an end elevation. Fig. 4 represents a transverse section 85 through the casing and one end of the gas-meter drum on line $x-x$, Fig. 2. Fig. 5 represents an end view of the gas-meter drum, showing by full lines the outlet-openings of the discharge end and indicating by dotted 90 lines the inlet-openings of the receiving end, both intended to illustrate the unison of the sealing and discharging action of the drum. Fig. 6 represents a detached face view of one 95 of the screw-vanes of the gas-drum. Figs. 7 and 8 represent, respectively, the receiving 100 and discharging end of the air-meter

drum, illustrating diagrammatically the comparative size of the inlet-openings and the discharge-openings of the screw measuring-compartments.

- 5 The outer cylinder or casing A, which contains the meter-drums, is preferably constructed of two half-cylinder sections provided with flanges *a*, which are secured together by rivets or bolts in a well-known manner. The cylinder A is supported on standards or legs *a'*. Within the cylinder A are mounted the two meter-drums B and C upon the same shaft *d*, which is journaled in suitable bearings in the gas and air supply pipes 10 *H* and *K* at the opposite ends of the cylinder. The drum B is styled the "propelling-drum" and is for measuring gas and driving or revolving the air-drum, and the drum C is styled the "induction-drum" and is for measuring and delivering air. The two drums are suitably spaced apart, so as to form a receiving-chamber D between their discharging ends for permitting the gas and air as discharged from the drums to intimately mix 15 together and for receiving the water displaced by the screw measuring-compartments during the revolution of the drums. The drums and their shaft are preferably placed centrally in the cylinder A in order to provide 20 a free space in which the drums may revolve and provide for the free circulation of liquid as it is displaced by the screw-vanes during the revolution of the drum. The propelling gas-drum B is constructed with a receiving-chamber *e* at its inlet end and with five spiral screw-vanes 1 2 3 4 5, placed equal distances apart and secured to the shaft *d*. Each screw-vane extends helically from the receiving or inlet end of the drum spirally a little more 25 than one half-turn to the discharge end of the drum, forming screw measuring-compartments of gradually-increasing diameters from the comparatively-narrow gas-inlets *u* at the receiving end to the comparatively-wide outlets *w* at the discharge end of the drum, as shown in Figs. 7 and 8, so that the gas will be passed through said compartments and discharged with the least possible resistance. 30 The screw measuring-compartments are not of increasing diameter radially from shaft *d*, but from side to side in cross-section approximately on lines of chords through the drum. The vanes at the receiving ends are provided each with two or more driving-shoulders *b*, which preferably extend radially from near the shaft to the shell of the drum, as shown in Figs. 4 and 6. These driving-shoulders *b* are at the receiving or inlet end of the drum exterior to the screw measuring-compartments and are styled "exterior" driving-shoulders. Within the drums the screw-vanes are also provided each with an interior driving-shoulder *b'*, as shown in Fig. 1. The measuring-compartments are formed by the 45 adjacent helical vanes and extend from the narrow inlets *u* to the wide outlets *w*—that

is, from the slot where the vane 2 overlaps the vane 1 and other similar slots to the discharge end of the drum, and the driving-shoulders *d* are on that portion of each vane 50 which is outside of the measuring-compartment, so that the gas bears upon the said shoulders before entering the compartments. The driving shoulders or offsets *b* taper from the periphery of the drum toward the shaft, 55 as shown, and in each vane terminate a short distance from the shaft, so that when the vane is above the liquid-line the driving-shoulders shall not extend down into the liquid. A smooth surface of the screw-vane is preferably near the center of the drum in order to avoid friction at that part which is always below the liquid-line. The speed at which the drum is to be revolved will be regulated by the number of driving-shoulders *b*. If a comparatively-high speed of rotation is required, 60 the number of shoulders will be increased. If a lower speed is required, the number of driving-shoulders will be decreased. The air inducing and measuring drum C is also constructed with a receiving-chamber *f* at the inlet end and with five helical screw-vanes, forming between them five screw measuring-compartments having comparatively-narrow inlets *x* at the receiving end and comparatively-wide outlets *y* at the discharge end, as 65 illustrated in Figs. 7 and 8, for reducing the resistance and facilitating the revolution of the drum in displacing the air and sealing liquid. The screw measuring-compartments 70 of the air-drum are preferably made with gradually-increasing diameters from side to side from the narrow inlet-openings *x* to the wide outlet-openings *y*, as indicated by dotted lines in Fig. 2, so as to facilitate the measuring and displacement of the air and to overcome resistance of the sealing liquid as the drum is revolved in the same. The vanes of the air-drum extend helically, or nearly so, a little more than one half-turn from the receiving end to the discharging end of the drum and are secured to the shaft and outer shell. With this construction of the vanes and screw measuring-compartments the inlet-openings of any one compartment will be 75 sealed in the liquid just before the outlet-opening of such compartment passes out of the liquid seal, so that the air after entering the screw-compartment must always be propelled toward the discharge end thereof, under the same pressure as the gas is displaced, 80 because the gas-pressure is cut off from the sister gas-chamber, and they are both discharging by the filling up of the compartments with liquid under one pressure and will always be moved forward in uniform and positively-measured quantities.

The gas-meter drum and the air-meter drum being secured to the same shaft, the air-drum will be revolved by the pressure of gas on the 85 driving-shoulders in the vanes of the gas-drum, which latter being revolved will,

through the medium of the shaft common to both drums, drive or revolve the air-drum, thus measuring and mixing positive and uniform proportions of gas and air. The pressure of gas alone on the driving-shoulders in the vanes at the receiving end of the gas-drum drives or revolves both drums.

It is to be noted that the gas-pressure is greatest and most effective at the receiving end of the gas-drum outside of the screw measuring - compartments, since such compartments are of increasing or expanding cross-section toward the discharge end, thus providing for expansion, and consequently reduced pressure and easy discharge of the inflowing gas, so that it will not act effectively, except at the initiatory, to drive the drum.

The heads of the cylinder A are provided with openings, in one of which is secured the elbow-pipe H for admission of gas and in the other of which is secured the elbow-pipe K for admission of air. A gas-supply pipe h connects with the elbow-pipe H. The elbow-pipes H and K project up near the top of the receiving-chambers e and f to prevent outflow of the sealing liquid under excessive pressure of gas. The water or other sealing liquid is maintained at the level of the dotted line z z in Figs. 2 and 4, and suitable supply and overflow pipes (not here shown) will be provided in practice.

A delivery-pipe L connects with the cylinder C, opening into the chamber D, for conducting the mixture of gas and air to the burner or other place of use. A water-gage n connects with one end of the cylinder for showing the height of the water in the same, and an index-dial m is secured to one end of the cylinder for indicating the number of feet of gas metered.

In constructing the gas and air mixing meter I am particular to so arrange the air-drum with relation to the gas-drum on the shaft that the outlets of the screw measuring compartments of the air-drum shall not be opposite the outlets of the measuring-compartments of the gas-drum. Preferably the outlets of one drum are arranged to discharge midway between the outlets of the opposite drum. By this arrangement of the relative positions of the discharging ends of the drums I obtain a positive sealing action in both drums, so that the gas under pressure will never have a clear passage from the outlet of the gas-drum through any one of the measuring-compartments of the air-drum for the reason that the measuring-compartment of the air-drum which is discharging air will be sealed at its inlet end and the measuring-compartment of the gas-drum which is discharging gas will at the same time be sealed at its inlet end.

With the above-described arrangement of the gas and air drums with the discharge-openings of one drum about midway between those of the other drum the sealing liquid which is displaced by the two drums will not be dis-

charged in opposing currents one against the other, which would tend to retard rotation of the drums, but will be discharged into the chamber D at different points in the revolution of the drums, so as not to interfere one with the other. This prevents any dragging in the revolution of the drums. By my improved construction such defects and difficulties are entirely overcome.

Gas being admitted under pressure through the elbow-pipe H into the receiving-chamber e of the gas-drum bears upon the driving-shoulders b of such screw-vanes as are above the surface z z of the sealing liquid and causes revolution of the drum B, thereby revolving the air inducing and measuring drum C. As the gas-drum B is revolved gas flows in through one of the narrow inlet-openings u, thereby gradually filling the screw-compartment between the adjacent vanes, as 1 and 2. Gas continues to flow into said compartment until the inlet-opening passes down into the liquid seal. The gas-pressure now continuing on the driving-shoulders of the successive or following screw-vane, which has been rising out of the liquid seal, continues the revolution of the drum, causing the outlet-opening of the compartment which has just been filled with gas to rise above the sealing liquid and permit the free discharge of gas from said compartment at the discharge end of the drum. In the above-described operation gas is discharged at the outlet end of the drum under the same pressure and velocity as the air from the sister chamber or measuring-compartment of the air-drum and both are intimately mixed in chamber D. This operation of filling the compartments with gas, sealing the inlets thereof, and unsealing the outlets thereof in successive order is continued so long as gas is admitted to the drum, and the mixture of gas and air is drawn off from chamber D.

The compartments, as indicated in Fig. 4, are so arranged that two of them are filling up with gas and two are discharging and one is idle at every position of the revolving drum, giving a balanced resistance at the discharging end.

The air-drum being attached to the same shaft as the gas-drum and revolving with the latter will take in air to the screw measuring-compartments and deliver it into the mixing-chamber D in practically the same manner as described with reference to the operation of the gas-drum B. As soon as any one screw-compartment of the air-drum is sealed at its receiving end it commences to discharge under pressure at the delivery end.

Under the construction and operation of the drums above described the gas and air are brought together under the same pressure and velocity in positively-measured proportions and a homogeneous mixture of gas and air under pressure is delivered to the burners. By halving a perfectly-homogeneous mixture complete combustion takes place at

once at the burner and all the carbonaceous matter is consumed at a high temperature, effecting great economy in the use of gas.

Having described my invention, what I claim as new, and desire to secure by Letters Patent, is—

1. In a mixing-meter, the propelling-drum constructed with screw-vanes, each having one or more driving-shoulders at the receiving end of the drum, outside of the measuring-compartments for causing the revolution of the drum by the pressure of gas against said shoulders, and means for supplying gas, substantially as described.
2. In a mixing-meter the propelling-drum having screw-vanes provided each with one or more exterior driving-shoulders at the receiving end of the drum, and an interior driving-shoulder in the interior of the measuring-compartments for causing revolution of the drum by the pressure of the gas against said shoulders and means for supplying gas, substantially as described.
3. In a mixing-meter a drum constructed of screw-vanes, forming screw measuring-compartments having comparatively narrow openings at the inlet end of the drum, of gradually-increasing width in cross-section and comparatively-wide openings at the discharge end of the drum for decreasing the resistance to the revolution of the drum and facilitating the flow or passage of both gas or aeriform fluid and the sealing liquid through the measuring-compartments, substantially as described.
4. A meter-drum divided by helical vanes into screw measuring-compartments having narrow inlets at the receiving end of the drum and wide outlets at the discharge end for decreasing the resistance and facilitating the revolution of the drum, substantially as described.
5. A gas and air mixing meter comprising a propelling gas-drum and an induction air-drum mounted on the same shaft, said gas-drum having vanes, provided, each with a driving-shoulder at the receiving end of the drum, and means for supplying gas to bear against said shoulders whereby said drum and

the air-drum are more readily revolved by 50 pressure of gas being metered, substantially as described.

6. A gas and air mixing meter comprising a propelling-drum constructed with vanes, one or more of which has an exterior driving-shoulder at the receiving end, and an air-measuring drum having narrow inlets at the receiving end and wide outlets at the discharge end, both drums being mounted on the same shaft, substantially as described. 55

7. In a mixing-meter the gas-drum constructed with a cylindrical shell, a shaft, a gas-receiving-chamber as a spiral screw-vanes between said receiving-chamber and the discharge end of the drum, said vanes having 65 each, one or more driving-shoulders in the receiving-chamber, and means for supplying gas to the latter chamber to bear against said shoulders, substantially as described.

8. In a mixing-meter the gas-drum constructed with a cylindrical shell and a gas-receiving chamber on a shaft, a gas-supply pipe therefor, spiral vanes forming screw measuring-compartments between said receiving-chamber and the discharge end of the drum, 75 said vanes having, each, one or more radial driving-shoulders in the receiving-chamber for revolving the drum by the pressure of gas, against said shoulders, substantially as described. 80

9. A gas and air mixing meter comprising a propelling gas-drum and an air-measuring drum mounted on the same shaft and each having a receiving-chamber, provided respectively with a gas and an air inlet, said 85 gas-drum having vanes provided each, at the receiving end of the drum, with a driving-shoulder, and said air-drum having smooth spiral vanes forming screw measuring-compartments between them, substantially as described. 90

In testimony whereof I affix my signature in presence of two witnesses.
